FILING DEVICE

Joseph C. Seyl, Evanston, Ill.

Application November 15, 1928
Serial No. 319,495

14 Claims. (Cl. 129—16)

The present invention relates generally to filing devices. More particularly the invention relates to that type of filing device which is used in connection with a cabinet drawer and comprises longitudinally adjustable partitions or plates for separating groups of papers from one another.

One object of the invention is to provide a filing device of this type which embodies novel means for conjointly locking the partitions in their various assigned positions, such means being independent of and in addition to the means whereby the partitions are supported so that they may be adjusted backwardly or forwardly in the cabinet drawer.

Another object of the invention is the provision of locking means of the aforesaid type which is operative in conjunction with the adjusting means to permit the partitions to be swung or tilted longitudinally for the purpose of facilitating access to the filed papers.

Another object of the invention is to provide a filing cabinet drawer in which the partitions are supported in an improved manner so that they are free to swing forwardly and backwardly to a limited degree and are longitudinally adjustable substantially the entire length of the drawer.

A further object of the invention is the provision of locking means for the partitions which is of new and improved construction and comprises elements that are mounted on the partitions and adapted to be manipulated manually in the event that individual adjustment of the partitions is desired.

A still further object of the invention is to provide a filing device which is of a unitary character and may be applied readily to a cabinet drawer having a channelled bottom and substituted for the usual follower-block and block-retaining means.

Another object of the invention is to provide an improved filing device which may be produced at a comparatively low cost and in which facility of adjustment and variability of action of the various parts are combined with durability and compactness of construction.

Other objects of the invention and the various advantages and characteristics of the present construction will be apparent from a consideration of the following detailed description.

The invention consists in the several novel features hereinafter set forth and more particularly defined by the claims at the conclusion hereof.

In the drawings which accompany and form a

part of this specification or disclosure and in which like numerals and characters of reference denote corresponding parts throughout the several views:

Figure 1 is a perspective view of a cabinet drawer provided with a filing device embodying one form of the invention, parts of the drawer being broken away for illustrative purposes. 60

Figure 1^a is a detail perspective view of one of the pin and slot connections between the push bar of the locking means and the bottom of the drawer. 65

Figure 2 is a transverse section of the member for supporting the partitions, disclosing the manner in which the locking members on the partitions are conjointly controlled. 70

Figure 3 is a fragmentary perspective view of one of the partitions, showing in detail the means whereby the partition is supported for longitudinal adjustment. 75

Figure 4 is a view partly in section and partly in elevation, illustrating the position normally assumed by the partitions; 80

Figure 5 is a perspective view of a drawer having incorporated therewith a filing device embodying a second form of the invention, parts being omitted for betterment in illustration; 85

Figure 6 is a fragmentary plan view showing the manner in which the lock bar of the partition locking means of the second construction is shifted transversely out of engagement with the locking pins on the partitions. 90

Figure 7 is a detail sectional view of one of the rack and pinion connections which operates to support the partitions of the Figure 5 arrangement so that they may be shifted backwardly and forwardly in the drawer; and 95

Figure 8 is a longitudinal sectional view of the locking pin for one of the partitions and the parts associated therewith.

The invention is exemplified in a filing device for use in connection with a drawer D of the type that is associated with a cabinet or analogous supporting structure and is operative to hold and store papers or like material. Two forms or embodiments of the invention are illustrated in the drawings. The device disclosed in Figures 1, 1^a, 2, 3 and 4 is of a unitary character and is particularly designed to be used in a drawer having a channelled bottom d. It comprises an elongated member 10 which corresponds in length to the drawer D and is adapted to support in longitudinal alignment a plurality of partitions or plates 11. The latter are preferably formed of sheet metal and form be- 110

tween them compartments 12 for the material to be filed. The width of the partitions is substantially the same as that of the drawer so that the compartments do not communicate with each other and the material cannot slip from one compartment to another. The top margins of the partitions are preferably extended so as to project upwardly of the sides of the drawer D. The member 10 is bent from a strip of sheet metal to form a bottom 13, sides 14 and a pair of outwardly projecting wings or side flanges 15. The bottom and sides of the supporting-member fit snuggly within the channel part of the drawer bottom d and together form an open top chamber 16. The wings or flanges extend laterally from the top margins of the sides 14 and rest directly upon the portions of the bottom d that are adjacent to the channel. The member 10 is held against displacement when in its operative position in the drawer D by means of tongues 17. These tongues are formed integral- 20 with the wings 15 and project downwardly through holes 18 punched in the bottom d. The lower ends of the tongues are bent or deflected laterally against the under face of the drawer-bottom to form an interlock between the member 11 and the drawer D. Said member 11 exemplifies partition supporting means which may be applied to a drawer of the channelled bottom type and is adapted to be substituted for or used in lieu of the usual follower-block and block-retaining means.

A rod 19 is positioned so as to extend longitudinally in the chamber 16. This rod is supported in spaced relation with respect to the bottom 13 by a pair of upstanding pieces 20 and 21 which are formed integral- 35 with the front and back ends of the bottom 13, respectively, and form closures for the ends of the chamber 16. Cotter pins or similar retaining devices 22 extend transversely through the ends of the rod 19 and abut against the outer faces of the pieces 20 and 21 to hold removably said rod in place. When these pins are withdrawn, the rod is free 45 to be slid axially out of its normal and operative position. Each of the partitions 11 embodies a pair of metallic plates 23 and 24. These plates fit against the front and back faces of the partition respectively and are rigidly secured in place adjacent the latter's bottom margin by rivets 25. Ears 23^a and 24^a are formed integral- 50 with the lower portions of the plates 23 and 24 respectively. Said ears depend from the plates and extend into the chamber 16. The rod 19 extends through longitudinally aligned holes 26 which are punched in the central portions of the ears 23^a and 24^a. By extending the rod in this manner the partitions are held against removal and are mounted so that they may be shifted back and forth substantially the entire length of the drawer D. An advantage of utilizing a mount of this character is that the partitions may be positioned readily when it is deemed desirable to increase or decrease the depth of the compartments 12. In addition it is not necessary to lift the filed papers or material from the forward compartments to the ones following in the event that said forward compartments become crowded beyond their capacity. The partitions 11 stand substantially vertically and the lower edges thereof rest upon the wings or flanges 15. The lower parts of the ears 23^a and 24^a engage the sides of the rod 19 and form abutments or stops which are operative in conjunction with the lower edges of the partitions

to prevent the partitions from being displaced from their operative or upstanding position. In practice it has been found to be desirable to have the partitions normally inclined backwardly and free to swing a slight distance forwardly for the purpose of facilitating access to the papers in the compartments. Because of this fact the holes 26 are made larger than the diameter of the rod 19 and so that the abutment-forming parts of the ears 23^a and 24^a are positioned with respect to the lower edges of the partitions to cause said partitions normally to extend backwardly at the desired angle and to permit of swinging or limited pivoted movement. The partitions 11 are held against transverse 80 displacement by stops 27 which lap and slidably engage the side portions of the rod 19. These stops are formed integral- 85 with the ears. The partitions 11 are assembled with respect to the supporting member 10 by holding them in their operative position with the ears of the plates 23 and 24 extending into the chamber 16, and shifting the rod 19 longitudinally through the holes 26 and into its supported position in the pieces 20 and 21. To remove the partitions from the member 10 it is only necessary to withdraw one of the cotter pins 22 and shift the rod 19 axially out of engagement with the ears 23^a and 24^a, it being understood that the rod may be so shifted when the member 11 is disconnected from the drawer D. The rod 19 together with said ears 23^a and 24^a exemplify means for supporting the partitions so that they are free to swing forwardly and backwardly to a limited degree and may be adjusted longitudinally substantially the entire length of the drawer.

Each of the partitions 11 is locked in its assigned position by an elongated vertically extending locking member 29. This member is preferably formed from a plate of sheet-metal and the upper end thereof laps a tab 11^a at the top margin of the partition. Said tab extends upwardly beyond the upper margin of the partition so that it may be used in swinging the partition back and forth. The member 29 engages against the front face of the partition and is slidably held by a sheath 30 so that it may be shifted vertically. The sheath is secured in place by side flanges 31 which are soldered or welded to the front face of the partition. The central or body part of the sheath is spaced a sufficient distance from the front face of the member 29 to permit member to drop, when permitted, in response to the action of gravity. The lower end of the locking member is provided with a pair of projections or teeth 32 and 33. The tooth 32 is shorter than the tooth 33 and is adapted to cooperate with a longitudinally extending stationary lock bar 34 to hold the partition in any of its assigned positions. The lock bar corresponds in length to the member 10 and has punched therein a longitudinal series of circular apertures 35. The latter are adapted to receive the tooth 32 of each member 29 for locking purposes. When the members 29 are raised, the teeth 32 are disengaged from the locking bar and the partitions are free to be shifted back or forth into the desired positions. When the members are released it is manifest that they slide downwardly in response to gravity and the teeth 32 drop into the subjacent apertures 35. The upper ends of the members 29 are recessed, as at 29^a, to form means whereby the partitions may be released individually from their locked positions. The bar 34 is formed from a strip of sheet-metal and is

suitably secured to the meeting margins of the side 14 and flange 15 at one side of the supporting member 10. The apertures 35 are arranged in close proximity to each other so that the partitions 11 may be locked in substantially any position along the member 10. The size of the apertures is such that movement of the teeth 32 is not impaired during rocking or swinging of the partitions.

10 The members 29 are conjointly locked and unlocked with respect to the bar 34 by an elongated push bar 37. This bar extends longitudinally in the chamber 16 and is somewhat shorter than the partition-supporting member 10. It is formed 80 from a strip or plate of sheet-metal and is bent to form a bottom 37^a, an upwardly inclined side wall 37^b and a shelf 37^c. The latter extends laterally from the upper margin of the side wall 37^b and is positioned beneath the lock bar 34. The bottom 37^a rests directly upon the central part 85 of the bottom 13. The inclined side wall 37^b is in the nature of a cam which when shifted sideways or transversely of the chamber 16 engages the teeth 33 on the locking members 29 and 90 raises them onto the shelf 37^c in which position the teeth 32 are disengaged from the lock bar 34 and the partitions are all free to be adjusted longitudinally in the drawer. The push bar 37 is adapted to be shifted transversely in response 95 to longitudinal movement imparted thereto, by means of a pair of fixedly mounted pins 38. These pins project upwardly from the bottom 13 and extend through a pair of diagonal slots 39 in the ends of the bar bottom 37^a. The slots are 100 preferably arranged so that when the push bar 37 is moved toward the front of the drawer the inclined side wall 37^b is operative to engage and shift upwardly the teeth 33. When the push bar 37 is moved backwardly the pin and slot 105 connections shift the shelf 37^c and the side wall 37^b out of contact with the teeth 33. This causes the locking member 29 to drop and results in the 110 conjoint locking of the partitions 11. Push and pull movement of the bar 37 is effected by a rod 115 40 which is connected to a lug 41 on the front end of said bar 37 and extends forwardly through a horizontal slot in the front of the drawer. A knob 42 is connected to the front end of the rod 40 so that the latter is readily shiftable from the 120 outside of the drawer.

In applying the filing device of Figures 1 to 4, the supporting member 10 is dropped into engagement with the channeled part of the drawer bottom after the usual follower-block and block-retaining means have been removed. The member is held against displacement in this position by means of the tongues 17 which are clinched under the portions of the drawer bottom that form the holes 18. The partitions 11 are adjusted into any desired position by raising the locking members 29 and sliding the partitions longitudinally of the rod 19. The raising of the members 29 may be accomplished individually by utilizing the recessed portions 29^a or conjointly by use of the push bar 37.

The filing device disclosed in Figures 5, 6, 7 and 8, is more or less an integral part of the drawer D' and comprises a sheet-metal partition 111. The drawer with which this partition 111 is associated consists of a bottom 112, sides 113, a front 114 and a back 115. The bottom is formed from a single plate of sheet-metal and has the side margins thereof bent to form a pair of hollow compartments 116. A pair of vertical sheet-metal racks 117 are positioned within the compartments 116 respectively and extend longitudinally therein. These racks are arranged outwardly of the sides 113 and embody base portions 117^a which are soldered or otherwise secured to the metal that forms the bottom parts of the compartments. The partition is provided at the bottom margin thereof with a transversely extending rod 118 having pinions 119 at the ends thereof. These pinions are located within the compartments 116 and mesh with the racks 117 to form movable connections whereby the partition is adjustably held in the drawer. The sides 113 are secured to upwardly extending flanges 120 at the side margins of the bottom and are arranged so that their bottom margins project 125 downwardly into compartments 116 and bear against the ends of the rods 118 in order to hold the pinions in mesh with the racks. The rods 118 are mounted in bearings 121 which are formed by bending the bottom margins of the partition 111 into tubular form. The upper margin of the partition is doubled back upon itself and is extended laterally to form abutments 122. These abutments cooperate with the top edges of the sides 113 to hold the partition in its back- 130 wardly inclined position. Adjustment of the partition is effected by swinging the latter vertically to disengage the abutments 122 from the subjacent edges of the sides and then moving it forwardly or backwardly into the desired position. During longitudinal movement the partition is supported solely by the rack and pinion connections by which means adjustment is 135 facilitated.

The central portion of the drawer bottom 112 is bent to form a depending channel member 123 consisting of a bottom 124 and sides 125. The latter members form a longitudinal open top chamber 126. The metal adjacent the central portion of the lower margin of the partition 111 forms a plate 127 which extends downwardly into this chamber 126. The bottom part of the plate 127 is bent upwardly to form a tubular bearing 128 in which is held a transversely extending pin 129. The latter projects beyond the 140 extension and is adapted to cooperate with a bar 130 to lock the partition in its assigned position. The lock bar 130 is formed from sheet-metal similarly to the partition 111 and comprises a bottom plate 130^a and an upwardly extending 145 side member 130^b. The latter has a longitudinal series of apertures 131 through which the exposed or outer ends of the pin 129 is adapted to extend. The bar 130 is slidably mounted so that it may be shifted transversely for the purpose 150 of effecting engagement or disengagement of the pin and the apertured side member 130^b. The mount whereby the bar 130 is confined to transverse sliding movement only comprises tongues 132. These tongues are formed integrally with 155 the bottom 124 and extend through and transversely of slots 133 which are cut in the side margin of the bottom plate 130^a opposite the side member 130^b. The tongues 132, in addition to forming a sliding connection for the bar 130, contact with one of the sides 125 to form longitudinal guides for a push bar 134. This push bar 160 fits upon the top face of the lock bar and is adapted to be reciprocated forwardly and backwardly by a rod 135. The ends of the bar 134 have formed therein diagonal slots 136. Upstanding pins 137 on the bottom plate 130^a project through these slots. When the push bar is reciprocated the portions which form the slots 136 operate to effect transverse shift movement 165

of the lock bar through the instrumentality of the pin and slot connections. The slots 136 are preferably arranged so that when the push bar 134 is pulled toward the front of the drawer the lock bar is shifted away from the pin 129 and the partition is released from its locked position. When the push bar is shifted toward the back of the drawer the lock bar is shifted transversely in the opposite direction and effects engagement of the pin and the side member 130^b. In this position of the locking members the partition is locked in place against longitudinal displacement. The apertures 131 are similar to the apertures 35 in that they are arranged in close proximity to each other and are of such size that movement of the pin 129 is not impaired when the partition is swung forwardly when access is desired to the filed papers. The pin 129 is slideable in the bearings 128 and is pressed outwardly by a spring 138 so that it yields when it is positioned out of alignment with respect to the apertures, and snaps into place when it is afterwards moved into alignment. The spring 138 is confined against axial displacement by a tongue 139 which is formed from the bearing 128. The movement of the pin 129 is limited by a tongue 140 which cooperates with a reduced stem portion of the pin and is also formed from the bearing 128. The rod 135 extends through a hole 141 in the drawer front 114 and is provided with a knob 142. The inward movement of the lock bar 130 is limited by a stop lug 143 which is secured to the inner face of said drawer front.

The filing devices disclosed herein consist essentially of but a few parts and may be manufactured at a comparatively low cost since sheet-metal may be used to good advantage throughout.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. The combination with a filing drawer, of a rod positioned in the bottom part and extending longitudinally of the drawer, a substantially vertical partition arranged with respect to the drawer and connected at the lower end thereof to the rod so that it is free to swing forwards and backwards to a limited extent and is adjustable longitudinally in the drawer by moving it rectilinearly only, and means for locking the partition in its various adjusted positions and at the same time permitting of limited swinging movement of said partition.

2. The combination with a filing drawer having a longitudinal channel formed in the bottom thereof, of a rod disposed in the channel, a partition extending substantially vertically and provided at its lower end with means whereby it is connected to the rod so that it is free to swing forwards and backwards to a limited extent and is adjustable longitudinally in the drawer by moving it rectilinearly only, and means including a movable element in the channel for locking the partition in its various adjusted positions and at the same time permitting of limited swinging movement of said partition.

3. In combination, a drawer, an upstanding partition disposed in the drawer and mounted so that it is free to be swung forwardly and backwardly and shifted bodily longitudinally of the

drawer, and means for locking the partition in its various shifted positions and at the same time permitting of limited swinging movement of said partition comprising a fixed, elongated member positioned longitudinally of the drawer and adjacent the drawer bottom and having a longitudinal series of apertures therein, and a coacting locking member movably mounted on the partition and having an end thereof shiftable into interlocked relation with the apertures. 80 85

4. In combination, a drawer, an upstanding partition disposed in the drawer and mounted so that it is free to be swung forwardly and backwardly and shifted bodily longitudinally of the drawer, and means for locking the partition in its various assigned positions and at the same time permitting limited swinging movement of the partition comprising an elongated, flat, sheet metal member mounted fixedly adjacent the drawer bottom and so that it extends lengthwise of the drawer and having a series of apertures extending substantially from one end thereof to the other, and a coacting locking member slideable vertically on the partition and arranged so that the lower end thereof is shiftable into interlocked relation with the apertures. 90 95

5. In combination, a drawer, an upstanding partition disposed in the drawer and mounted so that it is free to be swung forwardly and backwardly and shifted bodily longitudinally of the drawer, means for locking the partition in its various assigned positions and at the same time permitting limited swinging movement of the partition comprising an elongated, flat, sheet metal member mounted fixedly adjacent the drawer bottom and so that it extends lengthwise of the drawer and having a series of apertures extending substantially from one end thereof to the other, and a coacting locking member slideable vertically on the partition and arranged so that the lower end thereof is shiftable into interlocked relation with the apertures, and means controlled from the front of the drawer for shifting the locking member out of its operative position in order to release or unlock the partition so that it is free for longitudinal shift. 100 105 110

6. In combination, a drawer, an upstanding partition in the drawer mounted so that it may be shifted toward the front and back of the drawer, means for locking the partition in its various assigned positions comprising an elongated member positioned lengthwise of the drawer and adjacent the drawer bottom and having a series of apertures extending substantially from one end thereof to the other, and a coacting locking member movably mounted on the partition and arranged so that an end thereof is shiftable into interlocked relation with the aperture, and means controlled from the front of the drawer and including a transversely movable element, for shifting the locking member into an inoperative position in order to release the partition for shifting purposes. 115 120 125 130 135

7. The combination with a filing drawer having a longitudinal channel formed in the bottom thereof, of an upstanding partition disposed in the drawer and mounted so that it may be shifted toward the front and back of the drawer, and means for locking the partition in its various assigned positions comprising an elongated member mounted in a fixed position directly over and lengthwise of the channel and having a series of apertures extending from substantially one end thereof to the other, and a coacting locking member slideable vertically on the parti- 140 145 150

tion and arranged so that in response to the action of gravity the lower end thereof drops into interlocked relation with the apertures.

8. The combination with a filing drawer having a longitudinal channel formed in the bottom thereof, of an upstanding partition disposed in the drawer and mounted so that it may be shifted toward the front and back of the drawer, means for locking the partition in its various assigned 10 positions comprising an elongated member mounted in a fixed position directly over and lengthwise of the channel and having a series of apertures extending from substantially one end thereof to the other, and a coacting locking member slidable vertically on the partition and arranged so that in response to the action of gravity the lower end thereof drops into interlocked relation with the apertures, and means controlled from the front of the drawer and located within 20 in the channel, for raising the locking member into an inoperative position wherein the partition is free for shift thereof.

9. In combination, a filing drawer having a longitudinal channel formed in substantially the central portion of the bottom thereof, an upstanding partition in the drawer, a device confined 25 removably within the channel and operative to support the partition so that it is free to be swung forwardly and backwardly and shifted 30 bodily longitudinally in the drawer, and means for locking the partition in its various shifted positions and at the same time permitting of limited swinging movement of said partition.

10. The combination with a filing drawer having 35 a longitudinal channel formed in the bottom thereof, of a rod disposed lengthwise in the channel, a partition extending substantially vertical and provided at the lower end with means whereby it is connected to the rod so that it is supported for limited swinging movement and 40 bodily adjustment longitudinally in the drawer, means for locking the partition in its various adjusted positions and at the same time permitting of limited swinging movement of said partition, and means within the channel for releasing 45 the locking means in order to free the partition for longitudinal shift in the drawer.

11. In combination with a drawer, an upstanding partition disposed in the drawer and mounted 50 so that it is free to be swung forwardly and backwardly and shifted bodily longitudinally in the drawer, and means for locking the partition in its various assigned positions and at the same time permitting of limited swinging movement of 55 said partition comprising a locking member mounted on the partition so that it extends substantially horizontally, and an elongated member extending lengthwise of the drawer and having a longitudinal series of apertures from one end 60 thereof to the other for receiving one end of the locking member and mounted so that it is shiftable horizontally and transversely of the drawer

in order to bring the aperture opposite the coacting locking member into interlocked relation with the latter for partition-locking purposes.

12. The combination with a filing drawer having a longitudinal channel formed in the bottom thereof, of an upstanding partition disposed in the drawer and mounted so that it may be shifted toward the front and back of the drawer, and means for locking the partition in its various assigned 80 positions comprising a horizontally extending locking member connected to the bottom of the partition and disposed in the channel, and an elongated element extending longitudinally in the channel and having a longitudinal series of apertures from one end thereof to the other for receiving one end of the locking member and mounted so that it is shiftable horizontally and transversely of the drawer in order to bring the aperture opposite the coacting locking member into interlocked relation with the latter for partition-locking purposes.

13. The combination with a filing drawer having a longitudinal channel formed in the bottom thereof, of an upstanding partition disposed in the drawer and mounted so that it may be shifted toward the front and back of the drawer, and means for locking the partition in its various assigned 90 positions comprising a horizontally locking member connected to the bottom of the partition and disposed in the channel, an elongated element 95 extending longitudinally in the channel and having a longitudinal series of apertures from one end thereof to the other for receiving one end of the locking member and mounted so that it is shiftable horizontally and transversely of the drawer in order to bring the aperture opposite the coacting locking member into interlocked relation with the latter for partition-locking purposes.

14. The combination with a filing drawer having a longitudinal channel formed in the bottom thereof, of an upstanding partition disposed in the drawer and mounted so that it is free to be 100 swung forwardly and backwardly and shifted bodily longitudinally of the drawer, a pair of coacting elements carried respectively by the partition and the drawer bottom and operative to lock the partition in its various shifted positions and at the same time to permit of limited swinging movement of said partition, one of said 105 elements being movably mounted so that it may be disengaged with respect to the other element in order to release the partition so that it is free to be 110 shifted bodily longitudinally of the drawer, and an elongated element for shifting said one member movably mounted in and disposed lengthwise of the channel and embodying a push-rod extending through the front of the drawer whereby it may be manually manipulated.

JOSEPH C. SEYL.
